**TRANSFER MECHANISM FOR PROGRESSIVE
HEADERS AND THE LIKE**

Herbert L. Hoyt, Waterbury, and Erwin B. Byam, Wolcott, Conn., assignors to The Waterbury Farrel Foundry & Machine Company, Waterbury, Conn., a corporation of Connecticut

Application June 29, 1953, Serial No. 364,728

12 Claims. (Cl. 10—12)

This invention relates to metal-working machines such as a progressive header, nut former or the like, and particularly to transfer mechanism for such devices.

In metal-working machines where a blank is operated on progressively at a number of stations in the same machine, means are provided for transferring the blank from one station to the next. This function is usually performed by so-called transfer fingers, these fingers being arranged to receive and grip a blank when it is pushed out of one die and are then moved to a position opposite the next succeeding die or work station where the blank will be pushed out of the transfer fingers to be operated upon at the station to which it has been transferred. The present invention relates to the construction and operation of the transfer mechanism which transfers the blanks from one station to the next.

As illustrated, the apparatus comprises a carrier for the transfer fingers, which carrier is mounted for movement on the frame of the header or other metal-working machine. In the illustrated mechanism the carrier is mounted upon a pair of cranks which are rotated through an angle of slightly more than 180 degrees, the carrier having some relative movement with respect to the cranks so that its movement may be checked at the desired point or when it has moved approximately 180 degrees although the cranks may have a slight additional movement.

The carrier, therefore, is moved over an arcuate path and transfer fingers are attached to and carried by the carrier which grip the blank at one station and transfer it over an arcuate path of substantially 180 degrees to the next station.

Means are provided to open the transfer fingers at the proper time so that when a pair of fingers, carrying a work-piece, arrive opposite one of the die stations, they may be opened to permit a punch or other tool, upon the advance, to push the workpiece into the die and to receive a workpiece or blank pushed out of the die. In the present instance the two transfer fingers or finger holders of a co-operating pair are pivoted and the fingers are opened by the introduction of a wedge member or "splitter" between the upper ends of the finger holders. Each of these wedge members is carried upon a lever operated by a connecting rod or link pivoted to a second lever which carries a cam follower held in engagement with one of a plurality of cams mounted upon a rotating shaft. It will be apparent that as the first-named levers which carry the "splitters" for the transfer fingers are mounted upon the finger carrier, they are moved in an arcuate path with the latter while the second-named levers which carry the cam followers are mounted upon a fixed part of the machine. It is, therefore, necessary to so arrange the connecting link or rod between each pair of these levers so as to provide for relative movement of one with respect to the other.

Provision is also made for holding open the fingers of the transfer mechanism which carry the blank to the first operating station of the machine in case this becomes desirable to prevent a defective blank from being

2

fed to the machine. It sometimes occurs that when a new coil or supply of stock is fed into a machine of this character, a shortened blank will be cut off by the severing mechanism, and it is desirable that such a blank not be fed to the machine. According to the present arrangement, the operator may by pressing a push button hold the transfer fingers open so that such a workpiece will not be gripped by them but will be dropped and not carried to the first operating station of the machine.

10 One object of the invention is the provision of new and improved transfer mechanism for a progressive header or like machine.

15 A further object of the invention is to provide transfer mechanism for a machine of the character described wherein transfer fingers are attached to a carrier and provision is made for stopping the motion of the carrier at the proper point to align the transfer fingers with the die openings.

20 Still another object of the invention is to provide transfer mechanism for a machine of the character described wherein the carrier for the transfer fingers is operated by a crank mechanism, and provision is made for relative movement of the crank mechanism and the carrier in order to properly position the gripping fingers with respect to the dies.

25 Still another object of the invention is to provide a transfer mechanism for a machine of the character described, which transfer mechanism is provided with gripping fingers to receive and carry a work blank from one station to another and is also provided with means to open the work-gripping fingers at the proper time in the operation of the machine.

30 Still another object of the invention is to provide a transfer mechanism of the character described wherein means are provided to hold the gripping fingers of the transfer mechanism in open position when desired in order to prevent a defective blank from being fed to the machine.

35 To these and other ends the invention consists in the novel features and combinations of parts to be herein-after described and claimed.

In the accompanying drawings:

Fig. 1 is a front elevational view of the die block of a progressive header or like machine showing our improved transfer mechanism applied thereto;

Fig. 2 is a top plan view of the transfer mechanism;

Fig. 3 is a side elevational view thereof;

Fig. 4 is a sectional view on line 4—4 of Fig. 3;

Fig. 5 is a sectional view on line 5—5 of Fig. 1;

Fig. 6 is a sectional view on line 6—6 of Fig. 5; and

Fig. 7 is a detail sectional view on line 7—7 of Fig. 5.

To illustrate a preferred embodiment of our invention, we have shown a progressive header or like machine comprising a frame or bed 10 having a die bed 11 at the forward portion thereof. In the die bed are shown a cut-off station 12 where a length of rod or wire stock may be severed in the usual manner to form the workpiece or blank upon which the machine operates and a knock-out station 13 wherein may be mounted the usual knock-out rod to push the blank out of the severing knife and into the transfer fingers to be described hereinafter. It will be understood that the cut-off knife (not shown) may be of the usual form as may also be the mechanism for pushing the blank out of the cut-off knife into the transfer fingers.

As illustrated, the machine is provided with four operating stations at which are mounted the dies 15, 16, 17 and 18, and associated with each of these dies or stations is a pair of gripping fingers which are designed to be moved from one station to the next in order to transfer the blanks progressively from the push-out station to the

station 15 and thence in a step-by-step movement to the stations 16, 17 and 18, as is well known in the art.

As shown more especially in Figs. 3, 4 and 5, a segment gear 20 is rotatably mounted on the bed of the machine, the gear being secured to a shaft 21. This gear is rocked or oscillated by means of an arm 22 secured to the shaft, to the free end of which arm is pivotally connected the rod 23 which may be reciprocated by any usual means from one of the shafts of the machine, such, for example, as that shown in the Schaeffer and Hoyt application, Serial No. 156,674, filed April 18, 1950, now Patent No. 2,689,361 issued Sept. 21, 1954. Also rotatably mounted upon the bed of the machine are a pair of pinions 24, the teeth of which are in mesh with those of the gear 20.

Each of the pinions is secured to a shaft 25; and each of these shafts carries a crank 26 to which is secured a crank pin 27. Referring more especially to Fig. 5, a block 28 is mounted on bearings 29 on each of the crank pins 27 so that the pin may be free to rotate within the block. Each of the blocks 28 has an upward extension 30 extending and fitting snugly into an opening 31 in a finger carrier 32. A stud 33 is threaded into the extension 30 of the block 28 and the compression spring 34 surrounds this stud and bears at its lower end upon a bracket or cap 35 secured to the carrier.

It will be noted that, as shown in Figs. 5 and 6, the block 28 is disposed within a transverse opening 36 in the carrier 32 and that while this block fits the opening snugly on its side edges, it is smaller than the opening in a vertical dimension so as to permit a certain amount of relative movement between the block 28 which is carried by the crank 27 and the carrier 32. Secured upon the upper surface of the frame of the machine by screws 37 are stop blocks 38, these blocks, as shown in Figs. 5 and 6, being adapted to engage wear plates 39 secured to the lower surface of the carrier so as to properly position the carrier at the end of its stroke. It will be noted that the crank, due to the relative motion permitted between the block 28 and the carrier 32, may have a slight additional movement. Thus, even though the cranks might have a slight overtravel, the movement of the carrier may be stopped at the proper point to position the finger mechanism relatively to the die openings.

It may be noted that in the present instance there are four of the transfer finger mechanisms, each of which is mounted upon a block 40 slidably mounted in a slot 41 in the carrier 32. Adjustment of the block 40 in a vertical direction in the slot is effected by means of an adjusting screw 42 threaded through the block and engaging the upper surface of the carrier. The blocks 40 are held in place on the carrier by means of screws 42a. A pair of pivot pins 43 are secured to each of the blocks 40, and upon these pins are pivoted a pair of finger holders 44 to which are secured fingers 45. The upper ends of the finger holders above the pivot pins 43 are crossed, as shown, and rotatably mounted at the upper end of each of the finger holders is a roller 46. The fingers are urged toward closed position by a torsion spring 47, the ends of which bear against pins 48 rigidly secured to the finger holders 44 and the body of this spring is wrapped around a barrel 49 secured to the carrier by the bolts 43, the spring being held in place by a cap 50 of slightly larger diameter than the barrel. This cap may be formed integrally with the barrel.

Each pair of finger holders is opened by means of a wedge 51 carried at the lower end of a lever 52 pivoted at 53 to one of the brackets or caps 35. It will be understood that there are two of these brackets and, as there are four of the levers 52 (one for each pair of transfer fingers), two of the levers will be pivoted at each of the brackets. As shown in Fig. 3, the wedges 51 are adjustably secured to the lower ends of the levers 52 by screws 54, the adjustment in a direction toward and from the rollers 46 being effected by the adjusting screw 55. It will be apparent that when the levers 52 are moved from

the full to the dotted line position shown in Fig. 3, the wedges 51 will be moved inwardly between the rollers 46 and will tend to separate the upper ends of the finger holders 44 and likewise separate the fingers 45.

5 A wear plate 56 is secured to each of the adjusting blocks 40, this wear plate being held in place by a stud 57, which stud has a projecting end 58 which acts as a stop for adjusting screws 59 so that the position of the lower gripping ends of the fingers 45 may be adjusted. By this arrangement, the gripping ends of the fingers may be centered over the die openings in a horizontal direction. At the upper end of each of the levers 52 is a ball joint 60 connected to a clevis 61 by means of a slip pin 62. The center of this ball joint will thus be adapted to travel through an arc of approximately 180 degrees as indicated by the paths 63 (Fig. 1).

15 The clevis 61 is adjustably secured upon the forward end of a rod or link 64, the rear end of this rod having adjustably mounted thereon a clevis 65 similarly secured by a pin 66 to a ball joint 67 in a cam-lever 68 (Fig. 3) pivoted at 69 to a standard 70 mounted upon the bed of the machine.

20 The lever 68 is of bell crank form and is provided with a forwardly extending arm 71 which is urged toward the bed of the machine by a tension spring 72 secured at one end to the arm 71 and at the other end to a pin 73. Rotatably mounted on the lever 68 is a cam follower 74 which is urged by the spring 72 into engagement with a cam designated generally by the number 75, which cam is secured to the shaft 76. It will, of course, be understood that there are four of the rods 64 (one for each pair of transfer fingers), and likewise four of the levers 68 and four cams 75 on the shaft 76 which may be rotated by the power which actuates the machine.

25 It may be noted that each of the ball joints 67 is positioned at a point opposite the center of the corresponding arc 63 traversed by the ball joint 62 so that each rod 64 will form an element of a cone having a vertex at 67 so that the movement of the carrier 32 in its arcuate path carrying with it the levers 52 will not effect any movement of these levers or of the wedges 51 carried thereby.

30 Movement of the wedge to open the fingers at the proper time is effected by means of the lever 68 which is operated by the cam 75, the amount of opening being determined by adjusting the position of the wedge 51 with respect to the lever 52. The cam 75, as shown, comprises a fixed portion 77 keyed to the shaft 76 and two adjustable plates 79 provided with slots 80 and secured to the fixed cam portion 77 by bolts 81. With this arrangement the plates 79 may be adjusted to give the optimum timing to the opening and closing of the gripping fingers 45.

35 It will be apparent that as the cam 75 rotates the surface of the cam portions 77 and 79 acting against the follower 74 will move the lever 68 in a forward direction and, through the rods 64, will rock the levers 52 to swing the wedges 51 inwardly between the rollers 46 and open the fingers. As the roller 74 is urged against the cam by the spring 72, the wedge will be retracted when the roller is in engagement with the smaller portion of the cam and permit the fingers to be closed by the springs 47.

40 In certain instances it is desirable to hold the transfer fingers 45 open so as to prevent them from gripping and transferring an imperfect workpiece to the first operating station of the machine. This frequently occurs when a new coil of rod or wire is being fed into the machine and the blank severed by the cut-off knife is shorter than that required. To get rid of such a short length of stock provision is made for holding the fingers open so that it will not be gripped by them but will be dropped from the machine as scrap.

45 To this end a trip finger 82 is pivoted at 83 to a standard 84 upon the bed of the machine, this finger lying below an extension 85 on one of the levers 68, and in this instance the lever 68 which controls the opening and closing of the transfer fingers which feed the material to the

first station of the machine. This trip finger is lifted from the full line position shown in Fig. 3 to the dotted line position shown in this figure by the plunger 86 of a solenoid 87 which may be energized by means of a push button (not shown) on the control panel of the machine.

When the lever 68 is moved to the dotted line position shown in Fig. 3 and the operator energizes the solenoid 87, the finger 82 will be moved to a position to stand rearwardly of the finger 85 so as to hold the corresponding rod 64 in a forward position and thus maintain in an open position the corresponding transfer fingers 45. When these fingers are opposite the push-out station 13, as shown in dotted lines in Fig. 1, and a blank is pushed from the cut-off knife when the fingers are held in open position by the tripping finger 82, the blank will be allowed to drop from the machine. When the solenoid is de-energized so as to permit the trip finger 82 to drop to its full line position, shown in Fig. 3, the transfer mechanism will be permitted to follow its normal cycle of operations and will grip the blanks when they are positioned between the fingers.

In the operation of the machine a length of stock is fed through the cut-off die 12 and a suitable length will be severed by the usual knife (not shown) and transferred by the knife to the push-out station 13 where the workpiece will be pushed out of the knife into the first pair of fingers 45 which will then be in the dotted line position shown in Fig. 1. The crank shafts 25, which will be oscillated by the oscillation of the gear 20, will then move the carrier 32 in an arcuate path, thus transferring the workpiece from the push-out station to the first operating station or die 15. The end position of the carrier will be determined by the stops 38 and, as explained, the cranks 26 will be permitted a slight overtravel due to the loose connection between the blocks 28 and the carrier 32. The stop 38 will, therefore, serve to position the workpiece opposite the opening in the die 15 in a vertical direction. At the same time the blanks or workpieces will be carried from each of the stations 15, 16 and 17 to the succeeding station by the other pairs of fingers 45.

After the work operations have been performed on the blanks, the gear 20 will be oscillated in a reverse direction to move the transfer fingers rearwardly or to the left, as shown in Fig. 1, to be in position to receive and transfer another workpiece. At the proper time, the levers 68 will be operated by the cams 75 which will serve to rock the levers 52 about their pivots and move the splitter wedges 51 in between the roller 46 to open the fingers and allow the blanks to be pushed into the dies. The ball joints at each end of the rods or links 64 will permit the levers 52 to move with the carrier 32 relatively to the levers 68 which are mounted upon a fixed part of the machine without effecting any movement of the levers 52 and wedges carried thereby except when the levers 68 are actuated by the corresponding cams.

When desired, the operator may by energizing the solenoid 87 move the trip finger 82 behind the lever 68 with which it is associated to hold the levers 68 in a forward position and thus hold the fingers in open position. As illustrated, a trip finger 82 is associated only with the lever which operates the splitter wedge controlling the transfer fingers which receive the workpiece from the push-out station 13. It will be understood, however, that a similar mechanism may be associated with the other levers if desired.

While we have shown and described a preferred embodiment of our invention, it will be understood that it is not to be limited to all of the details shown, but is capable of modification and variation within the spirit of the invention and within the scope of the claims.

What we claim is:

1. A header or like mechanism having a frame and a plurality of dies carried thereby at separate stations, means for transferring a blank from one station to the

next comprising an oscillating carrier movable with respect to the dies, a plurality of pairs of cooperating transfer fingers supported by the carrier, spring means to urge each pair of said fingers together to grip a blank, crank means on the frame to oscillate said carrier, means on the carrier to effect a separating movement of said fingers and actuating means on the frame pivotally connected to said last-named means to actuate the same.

2. A header or like mechanism having a frame and a plurality of dies carried thereby at separate stations, means for transferring a blank from one station to the next comprising an oscillating carrier movable with respect to the dies, a plurality of pairs of cooperating transfer fingers supported by the carrier, spring means to urge each pair of said fingers together to grip a blank, crank means on the frame to oscillate said carrier, means on the carrier to effect a separating movement of said fingers, said means comprising a wedge member movable to position to force said fingers apart, and actuating means on the frame pivotally connected to said last-named means to actuate the same.

3. A header or like mechanism having a frame and a plurality of dies carried thereby at separate stations, means for transferring a blank from one station to the next comprising a carrier movable with respect to the dies, a pair of finger holders carrying cooperating transfer fingers supported by the carrier, spring means to urge said fingers together to grip a blank, means on the carrier to effect a separating movement of said fingers, said means comprising a lever pivoted to the carrier, wedge means rigidly mounted on said lever to enter between said finger holders and force the fingers apart, and actuating means on the frame pivotally connected to said lever to actuate the latter.

35. 4. A header or like mechanism having a frame and a plurality of dies carried thereby at separate stations, means for transferring a blank from one station to the next comprising a carrier movable with respect to the dies, a pair of finger holders carrying cooperating transfer fingers supported by the carrier, spring means to urge said fingers together to grip a blank, means on the carrier to effect a separating movement of said fingers, said means comprising a lever pivoted to the carrier, wedge means adjustably mounted on said lever to enter between said finger holders and force said fingers apart, and actuating means on the frame pivotally connected to said lever to actuate the latter.

5. A header or like mechanism having a frame and a plurality of dies carried thereby at separate stations, means for transferring a blank from one station to the next comprising an oscillating carrier movable with respect to the dies, a plurality of pairs of cooperating transfer fingers supported by the carrier, spring means to urge each pair of said fingers together to grip a blank, crank means on the frame to oscillate the carrier, means on the carrier to effect a separating movement of said fingers, said means comprising a lever pivoted on the carrier, means on said lever to force said fingers apart, actuating means for said lever carried upon the frame, and connecting means pivotally connecting said actuating means and said lever to move the latter in timed relation to the movement of the carrier.

6. A header or like mechanism having a frame and a plurality of dies carried thereby at separate stations, means for transferring a blank from one station to the next comprising an oscillating carrier movable with respect to the dies, a plurality of pairs of cooperating transfer fingers supported by the carrier, spring means to urge each pair of said fingers together to grip a blank, crank means on the frame to oscillate the carrier, means on the carrier to effect a separating movement of said fingers, said means comprising a lever pivoted on the carrier, means on said lever to force said fingers apart, cam-actuated means on the frame, means pivotally connecting said 70 cam-actuated means to said lever to move the latter,

7. A header or like mechanism having a frame and a plurality of dies carried thereby at separate stations, means for transferring a blank from one station to the next comprising an oscillating carrier movable with respect to the dies, a plurality of pairs of cooperating transfer fingers supported by the carrier, spring means to urge each pair of said fingers together to grip a blank, crank means on the frame to oscillate the carrier, means on the carrier to effect a separating movement of said fingers, said means comprising a lever pivoted on the carrier, means on said lever to force said fingers apart, cam-actuated means on the frame, means pivotally connecting said cam-actuated means to said lever to move the latter, and a cam rotatably mounted on the frame to engage said cam-actuated means.

8. A header or like mechanism having a frame and a plurality of dies carried thereby at separate stations, means for transferring a blank from one station to the next comprising an oscillating carrier movable with respect to the dies, a plurality of pairs of cooperating transfer fingers supported by the carrier, spring means to urge each of said fingers together to grip a blank, crank means on the frame to oscillate the carrier, means on the carrier to effect a separating movement of said fingers, said means comprising a lever pivoted on the carrier, means on said lever to force said fingers apart, a second lever pivotally mounted on the frame, cam means to actuate said second lever, a link connecting said levers whereby actuation of the second lever moves the first lever to force the fingers apart, and the ends of said link being swiveled to said levers to permit oscillating movement of the carrier with respect to the frame.

9. A header or like mechanism having a frame and a plurality of dies carried thereby at separate stations, means for transferring a blank from one station to the next comprising a carrier movable with respect to the dies, a plurality of pairs of cooperating transfer fingers supported by the carrier, spring means to urge said fingers together to grip a blank, means on the carrier to effect a separating movement of the fingers of at least one of said pairs, said means comprising a wedge member movably mounted on the carrier, means on the frame connected to said wedge member to move it to position to force said fingers apart, and manually actuated means to hold said wedge member in said position during the movement of the carrier to prevent the gripping of a blank by said fingers.

10. A header or like mechanism having a frame and a plurality of dies carried thereby at separate stations, means for transferring a blank from one station to the next comprising a carrier movable with respect to the dies, a plurality of pairs of cooperating transfer fingers supported by the carrier, spring means to urge said fingers together to grip a blank, means on the carrier to effect

a separating movement of the fingers of at least one of said pairs, said means comprising a wedge member movably mounted on the carrier, means on the frame connected to said wedge member to move it to position to force said fingers apart, and manually actuated electrically operated means to hold said wedge member in said position during the movement of the carrier to prevent the gripping of a blank by said fingers.

11. A header or like mechanism having a frame and a plurality of dies carried thereby at separate stations, means for transferring a blank from one station to the next comprising a carrier movable with respect to the dies, a pair of cooperating transfer fingers supported by the carrier, spring means to urge said fingers together to grip a blank, means on the carrier to effect a separating movement of said fingers, said means comprising a lever pivoted on the carrier, means on said lever to force said fingers apart, a second lever mounted on a fixed part of the frame, means connecting said first and second levers.

15 20 25 30 35 40 45

means to actuate the former from the latter, and a manually actuated trip member adapted to engage said second lever to hold it in its actuated position to maintain said fingers apart during the movement of the carrier to prevent the gripping of a blank by said fingers.

12. A header or like mechanism having a frame and a plurality of dies carried thereby at separate stations, means for transferring a blank from one station to the next comprising a carrier movable with respect to the dies, a pair of cooperating transfer fingers supported by the carrier, spring means to urge said fingers together to grip a blank, means on the carrier to effect a separating movement of said fingers, said means comprising a lever pivoted on the carrier, means on said lever to force said fingers apart, a second lever mounted on a fixed part of the frame, means connecting said first and second levers to actuate the former from the latter, a trip member adapted to engage said second lever to hold it in its actuated position to maintain said fingers apart during the movement of the carrier to prevent the gripping of a blank by said fingers, and manually operated electrical means to actuate said trip member.
